United States Patent Office

Des. 211,626
Patented July 9, 1968

211,626

PACKAGING CONTAINER FOR FOOD PRODUCTS OR THE LIKE

Walter Kerut, Queens, N.Y., assignor to Lily-Tulip Cup
Corporation, New York, N.Y., a corporation of
Delaware

Filed Oct. 18, 1967, Ser. No. 9,046

Term of patent 14 years

(Cl. D9—220)

FIG. 1

FIG. 2

FIGURE 1 is a top plan view of a packaging container for food products or the like, showing my new design;

FIGURE 2 is an elevational view thereof;

FIGURE 3 is a bottom plan view thereof;

FIGURE 4 is an enlarged fragmentary cross-sectional view thereof taken along line 4-4 of FIGURE 2; and

FIGURE 5 is an enlarged fragmentary cross-sectional view thereof taken along line 5-5 of FIGURE 1.

I claim:

The ornamental design for a packaging container for food products or the like, substantially as shown.
